WILLIAM SHAKESPEARE, JR., AND WILLIAM SCHMID, OF KALAMAZOO, MICHIGAN.
ASSIGNORS TO WILLIAM SHAKESPEARE, JR., COMPANY, OF KALAMAZOO, MICHIGAN.

CARBURETER.

1,179,663.

Specification of Letters Patent. Patented Apr. 18, 1916.

Application filed December 16, 1912. Serial No. 736,996.

To all whom it may concern:

Be it known that we, WILLIAM SHAKESPEARE, JR., and WILLIAM SCHMID, citizens of the United States, residing at Kalamazoo, Michigan, have invented certain new and useful Improvements in Carbureters, of which the following is a specification.

This invention relates to improvements in carbureters. The main objects of this invention are,—first, to provide an improved carbureter in which the proper relative proportions of fuel and air are maintained through varying running conditions of the engine. Second, to provide an improved carbureter in which the air and fuel valves are simultaneously operated. Third, to provide an improved carbureter which is capable of being adjusted for proportioning the air and fuel and one in which the proportion is maintained throughout the scope of adjustment of the throttle. Fourth, to provide in a carbureter, an improved valve mechanism which is not likely to get out of repair or adjustment in use. 25 Further objects, and objects relating to structural details, will definitely appear from the detailed description to follow.

We accomplish the objects of our invention by the devices and means described in 30 the following specification.

The invention is clearly defined and pointed out in the claims.

A structure which is a preferred embodiment of our invention is clearly illustrated 35 in the accompanying drawing forming a part of this specification, in which:

Figure I is a side elevation of our improved carbureter, the starting valve and the air valve operating mechanism being shown 40 in front elevation. Fig. II is a vertical central section of the carbureter proper. Fig.

III is a horizontal section on a line corresponding to the broken line 3—3 of Fig. II. Fig. IV is an end elevation of the air supply 45 conduit of the carbureter. Fig. V is a transverse vertical section through the air supply conduit taken on a line corresponding to line 5—5 of Fig. II. Fig. VI is a detail vertical section on a line corresponding to the broken line 6—6 of Fig. I, showing details of the priming mechanism. Fig. 50 VII is a detail perspective of the air valve 38 and its mountings. Fig. VIII is a perspective view of the bearing rollers 42 and

their retaining ring. Fig. IX is a detail 55 plan view of the valve lever 49 and the fuel valve adjusting member 58. Fig. X is a detail section on a line corresponding to line 10—10 of Fig. II. Fig. XI is a perspective view of the friction washer 59. Fig. XII 60 is a detail vertical section through the primer and temperature control mechanism, taken on a line corresponding to line 12—12 of Figs. I and XIII. Fig. XIII is a front view of the primer and temperature control 65 mechanism with the index plate 74 removed. In the drawing similar reference characters refer to similar parts throughout the several views, and the sectional views are taken looking in the direction of the little arrows 70 at the ends of the section lines.

Briefly considered, our improved carbureter comprises a chambered body having a mixing chamber and an air inlet or air supply chamber. Supported centrally within this body is a carbureting chamber arranged to deliver to the mixing chamber. Fuel is delivered centrally to the carbureting chamber. A mixing chamber valve is provided which controls the delivery of air 80 to the mixing chamber from the inlet chamber. This valve coacts with an annular seat so that when the valve is opened, the air is delivered to the mixing chamber through an unobstructive annular port. The carbureting chamber delivers to the mixing chamber centrally above this port. The fuel nozzle delivers centrally to the carbureting chamber and an annular carbureting chamber valve is provided to coact with the 90 nozzle providing when open an unobstructive air inlet port for the carbureting chamber to which the fuel is centrally delivered. The needle valve is arranged to project into the fuel nozzle centrally thereof. These 95 valves are all mounted so as to be simultaneously adjusted, as will appear from the following detailed description.

The body of our improved carbureter, for convenience in manufacturing and assembling, is preferably formed of members 1, 2 and 3, the member 3 being the air supply conduit member. The members 1 and 2 are chambered, or provided with passages, the passage in the member 1 constituting a 100 mixing and delivery passage of the carbureter. The member 2 is provided with an annular fuel reservoir 4. The member 1 is 105

provided with an annular seat or internal shoulder 5 into which the member 2 fits. The member 2 is provided with an annular shoulder 6 with which the member 3 engages. The parts 2 and 3 are secured together by the member 7 having a stem-like portion arranged through the cross bar 8 on the member 2 and the cap nut 9 arranged through the bottom of the member 3 and threaded upon the member 7. At one side the reservoir 4 is provided with an offset inlet chamber 10 provided with a nipple 11 to which the supply pipe is connected. The inlet valve 12 is controlled by the annular float 13 which acts on the lever 14 pivoted at 15 and slotted to engage the reduced portion 16 of the valve stem. The lever 14 is forked to embrace the body of the carburetor, as shown in Fig. III. The lever is connected 20 to the float by means of the pins 17. The chamber 10 is provided with a removable cover 18 which may be removed to afford access to the valve members. The pivot 15 for the lever 14 is carried by the bracket 19 mounted on the cover plate 18, the bracket being provided with downwardly projecting pivot ears 20 between which the lever is arranged. The cover plate 18 is provided with a bushing 21 through which the stem 20 of the valve projects. The cap 22 for the valve stem is removably mounted upon the bearing or bushing 21 so that by removing the same, the valve stem is exposed so that it may be turned in its seat for clearing the 25 valve or the valve seat. The inlet chamber 10 is provided with a well or depression in its bottom and with a drain cock 23 so that the sediment collected in the well may be drawn off.

40 The member 1 of the body in the structure illustrated is provided with a water jacket 24 having suitable connections, the object being to supply heated water to the jacket when desired.

45 The cross bar 8 is provided with a fuel passage 25 communicating with the reservoir 4, while the member 7 is provided with a passage 26 registering therewith. The member 7 is provided with a valve seat 27 for the needle fuel valve 28. This valve seat 27 is formed in the valve member 29 seated in the upper end of the member 7 and communicating with the passage thereof, as shown in Fig. II. The member 7 is 50 provided with a plurality of air passages 30 opening into the passage of the body member 2 at their lower ends and delivering at the upper end of the member 7 about the fuel valve. The fuel valve is surrounded 55 by the carbureting chamber member 31 which opens at its upper end into the mixing chamber. The air passages 30 are controlled by the valve 32 which is secured to the carbureting chamber member 31 and 60 coacts with the valve member 29 which is

tapered upwardly as shown. The valve 32 is opened and closed by vertical movement as is also the fuel valve 27.

The mixing chamber member 31 and the fuel valve 28 are both carried by the tubular actuating member 33, the stem 34 of the fuel valve 28 being arranged longitudinally through the member 33 and threaded into the same for adjustment, while the carbureting chamber member 31 is connected thereto 75 through the arms 35 having a ring 36 at their lower ends embracing the carbureting chamber member 31 and the ring 37 at its upper ends embraces the lower end of the member 33. The lower end of the adjusting 80 member 33 and of the ring 37 are beveled as shown, the discharge for the carbureting chamber being between these members and the upper end of the carbureting chamber. The throttle valve 38 is mounted on the 85 shoulder 39 on the carbureting chamber member 31. This throttle valve 38 coacts with an annular shoulder-like seat 40 within the body member 2. By thus arranging the parts, the throttle valve 38, the fuel valve 90 28 and the carbureting chamber air inlet valve 32 are simultaneously and uniformly opened and closed. The valves move vertically in opening and closing and this is effected by rotative movement of the member 95 33.

The member 31 is provided with cams 41 coacting with rollers 42 traveling on the cam roller supporting member 44 which is mounted on a shoulder on the members 7. 100 The roller retaining ring 43 is loosely mounted on the member 44. The member 33 is provided with a bearing member 45 coacting with the bearing member 46 carried by the body of the carburetor, a ball bearing being provided in the structure illustrated. The actuating member 33 is held yieldingly downward by the coiled spring 47, the lower end of which engages the ring 37, its upper end engaging the bearing member 45. On the upper end of the member 33 is a head 48 to which the operating lever 49 is attached. The head is secured to the member 33 by means of the sleeve nut 50 arranged in the chamber 51 in the head 115 and threaded into the tubular member 33, the valve stem 34 being arranged through this sleeve-like nut as shown in Fig. II. The head 48 is supported in a bearing 52 formed in the upper side of the body member 1. The stroke of the lever is regulated by the stop 53, on the lever head 48, coacting with the stop member 54 having stop shoulders 55 and 56. The stop member 54 is adjusted by means of the worm 57 the 120 stop member being suitably toothed to coact with the worm. The fuel valve projects from the member 33 and its head is provided with a finger piece 58 bearing suitable scale indicia. The fuel valve is retained in 130

its adjusted position by the friction washer 59 having fingers 60 engaging grooves 61 in the head to prevent its turning, the spring 62 being arranged to bear against 5 the washer. With the parts thus arranged, the fuel valve and carbureting chamber air inlet valve, and the throttle valve are all operated from the lever 49.

To control the temperature of the air 10 passing to the carbureter, the conduit member 3 is provided with a cold air inlet port 63 and with a hot air inlet 64 adapted to be connected to a suitable source of supply, as a coil (not shown) heated by the exhaust. 15 The cold air inlet and the hot air inlet are both controlled by the cylindrical valve 65 having a transverse port 66' of such length that the valve may be adjusted to admit both the cold air and the hot air in varying proportions or to shut off the cold air or the hot air entirely and take only hot or cold air. The valve 65 is controlled by the lever 66 arranged in a convenient position, as upon the dash 67 of a car when 20 our improved carbureter is used on a motor car engine. The lever 66 is provided with a sleeve-like bearing member 68 arranged through the bearing 69 of the support 70, which is mounted on the front of the dash, 25 the bearing 69 being arranged through the dash. On the rear end of the lever bearing member 68 is an arm 71 connected by the link 72 to the arm 73 on the valve 65. A dial 74 having suitable temperature indicia 30 is mounted on the support 70. The edge of the dial is notched, while the lever is provided with a spring pressed pawl 75 adapted to engage the notches for retaining the lever in its adjusted position. The finger 35 piece of the lever serves as an index. The numerals of the index dial indicate the position the lever should be adjusted to for the different temperatures. For instance, the lever 66 is shown adjusted to 40° and 40 the air inlet valve is open to take hot and cold air approximately half in half. In a temperature of 80°, the lever would be adjusted to 80. In a temperature of zero, it would be adjusted to zero and a greater portion 45 of the air taken would be through the hot air port. At ten below zero only hot air would be taken. This is found to be a very advantageous feature in the proper control of the carbureter and in securing the best results. 50 A primer valve 76 is arranged above the reservoir 4 in a chamber 77 provided therefore in the body member 1. The valve seat 87 for the valve 76 is formed in the wall of 55 the body member 1. The valve chamber 77 is connected by the tube 79 with the oil reservoir, the tube depending into the same as shown in Fig. VI. The valve is held 60 yielding seated by means of the spring 80, one end of which bears against the collar 81 on

the valve stem, the other being seated in the closure 82 for the chamber 77, the valve stem projecting through the end of the closure. The valve stem is provided with a disk-like head 83 with which the eccentric pin 84 on 70 the rotating valve actuating member 85 contacts. The valve actuating member 85 is supported in a bearing 86 carried by the closure member 82. The actuating member 85 is connected by the flexible shaft 87 to the 75 spindle 88 of the lever 89, the spindle 88 being journaled in the bearing sleeve 68 of the lever 66. See Figs. I, XII and XIII. The lever 89 is provided with a lug 90 coacting with a lug 91 on the lever 66. 80 These lugs engage when the levers are swung to certain positions, for instance, when the primer control is adjusted to start the engine at 10° temperature, the air control is shifted at the same time to the 10° 85 position if it has not been previously adjusted to such position. The primer control lever may, however, be returned to its running position without moving the air control lever. When the lever 66 is swung 90 against the boss-like stop 92, the cold air port is fully opened and the hot air entirely cut off. This also swings the lever 89 against the stop 93 or to its closed or running position. By this arrangement, a very effective priming is secured which greatly facilitates the starting of the engine. Further, if the primer be opened during the last few strokes of the engine when stopping 95 the same, the cylinders will receive such a 100 charge of fuel that the engine can usually be started from the spark even for a considerable period after stopping.

Certain features of the structure here described are illustrated and broadly claimed in our Letters Patent No. 1,107,713, issued to us August 18, 1914, the present structure being in some respects a modification and improvement upon the structure there illustrated, and certain features described in 110 this application are claimed in a divisional application filed June 13, 1913, Ser. No. 773,412.

We have illustrated and described our improved carbureter in a structure in which 115 we have embodied the same. We have not attempted to illustrate or describe various modifications which we contemplated as such modifications will it is believed be readily understood by those skilled in the art to 120 which this invention relates from the disclosure herein made. We desire, however, to be understood as claiming our inventions specifically in the form illustrated as well as broadly within the scope of the appended 125 claims.

Having thus described our invention, what we claim is new and desire to secure by Letters Patent is:

1. In a carbureter, the combination of a 130

- chambered body provided with an annular shoulder-like valve seat, the chamber above said valve seat constituting a mixing chamber and that below an air supply chamber, 5 a carbureting chamber member provided with a carbureting chamber delivering to said mixing chamber, a mixing chamber valve mounted on said carbureting chamber member to coact with said valve seat, an inlet member having a fuel inlet passage 10 therein provided with a fuel nozzle delivering to said carbureting chamber and having a plurality of air passages disposed to deliver to said carbureting chamber about 15 said fuel nozzle and communicating with said air supply chamber, a carbureting chamber air valve carried by said carbureting chamber member, a needle fuel valve carried by said carbureting chamber member to coact with said fuel nozzle, and means 20 for vertically adjusting said carbureting chamber member.
2. In a carbureter, the combination of a chambered body provided with an annular 25 valve seat, the chamber above said valve seat constituting a mixing chamber and that below an air inlet chamber, a carbureting chamber member provided with a carbureting chamber delivering to said mixing 30 chamber, a mixing chamber valve mounted on said carbureting chamber member to coact with said valve seat, a carbureting chamber air inlet valve mounted on said carbureting chamber member for adjustment 35 therewith, a fuel valve mounted on said carbureting chamber member for adjustment therewith, and means for vertically adjusting said carbureting chamber member.
3. In a carbureter, the combination of a 40 mixing chamber, a carbureting chamber member provided with a carbureting chamber delivering to said mixing chamber, a tapered fuel nozzle projecting into said carbureting chamber, there being a 45 plurality of air inlet passages disposed to deliver about said nozzle, an annular carbureting chamber air inlet valve mounted on said carbureting chamber member to embrace and coact with said fuel delivery nozzle, a rotatably and longitudinally adjustable actuating member for said carbureting chamber member, a needle fuel valve arranged longitudinally of said actuating member to coact with said fuel nozzle, a 55 cam on said carbureting chamber member, rollers coacting with said cam whereby when said actuating member is rotated the carbureting chamber member is moved vertically, and a mixing chamber valve mounted 60 on said carbureting chamber member.
4. In a carbureter, the combination of a mixing chamber, an adjustable carbureting chamber member provided with a carbureting chamber delivering to said mixing chamber, said carbureting member being mounted for 65 longitudinal adjustment, a fuel nozzle delivering to said carbureting chamber, a needle fuel valve mounted on said carbureting chamber member for adjustment therewith, and means for adjusting said carbureting chamber member, said fuel valve being adjustably mounted on said carbureting chamber member.
5. In a carbureter, the combination of a mixing chamber, a carbureting chamber member provided with a carbureting chamber delivering to said mixing chamber, a fuel nozzle delivering to said carbureting chamber, an annular carbureting chamber air inlet valve mounted on said carbureting chamber member to coact with said fuel nozzle, and means for rotating 70 by said cam.
6. In a carbureter, the combination of a mixing chamber, a carbureting chamber member provided with a carbureting chamber delivering to said mixing chamber, a fuel nozzle delivering to said carbureting chamber, an annular carbureting chamber air inlet valve mounted on said carbureting chamber member to coact with said fuel nozzle, a longitudinally adjustable actuating member for said carbureting chamber member, a needle fuel valve arranged longitudinally of said actuating member to coact with said fuel nozzle, and a mixing chamber valve mounted on said carbureting chamber member.
7. In a carbureter, the combination of a mixing chamber, a carbureting chamber member provided with a carbureting chamber delivering to said mixing chamber, said carbureting member being mounted for longitudinal adjustment, a fuel nozzle delivering to said carbureting chamber, a needle fuel valve mounted on said carbureting chamber member for adjustment therewith, a mixing chamber valve mounted on said carbureting chamber, and means for adjusting said carbureting chamber member, said fuel valve being adjustably mounted on said carbureting chamber member.
8. In a carbureter, the combination of a mixing chamber, a carbureting chamber member provided with a carbureting chamber delivering to said mixing chamber, said carbureting member being mounted for longitudinal adjustment, a fuel nozzle delivering to said carbureting chamber, a needle fuel valve mounted on said carbureting chamber member for adjustment therewith and to coact with said nozzle, a carbureting chamber air inlet valve mounted on said carbureting chamber member for adjustment therewith, a mixing chamber valve mounted on said carbureting chamber, and means for adjusting said carbureting chamber member, said fuel valve being adjustably mounted on said carbureting chamber member.

said carbureting chamber member for adjustment therewith, a mixing chamber valve mounted on said carbureting chamber, and means for adjusting said carbureting chamber member.

9. In a carbureter, the combination of a chambered body provided with an annular valve seat, the chamber above the seat constituting a mixing chamber and that below an air inlet chamber, an adjustable carbureting chamber member provided with a carbureting chamber, a mixing chamber valve mounted on said carbureting chamber member to coat with said mixing chamber valve seat providing when open an unobstructed annular port, said carbureting chamber being arranged to deliver to said mixing chamber centrally above said port, a fuel nozzle disposed to deliver centrally to said carbureting chamber, an annular carbureting chamber air inlet valve mounted on said carbureting chamber member for adjustment therewith and surrounding said nozzle providing an annular air inlet port for said carbureting chamber, a needle fuel valve carried by said carbureting chamber member and extending into the delivery orifice of said fuel nozzle to provide an annular fuel port delivering centrally of said carbureting chamber air inlet port, and means for adjusting said carbureting chamber member whereby said valves are simultaneously adjusted.
10. In a carbureter, the combination of a chambered body provided with an annular valve seat, the chamber above the seat constituting a mixing chamber and that below an air inlet chamber, an adjustable carbureting chamber member provided with a carbureting chamber, a mixing chamber valve mounted on said carbureting chamber member to coat with said mixing chamber valve seat providing when open an unobstructed annular port, said carbureting chamber being arranged to deliver to said mixing chamber centrally above said port, a fuel nozzle disposed to deliver centrally to said carbureting chamber, an annular carbureting chamber air inlet valve surrounding said nozzle providing an annular air inlet port for said carbureting chamber, a needle fuel valve, and means for adjusting said valves.

viding an annular air inlet port for said carbureting chamber, a needle fuel valve carried by said carbureting chamber member, and means for adjusting said carbureting chamber member whereby said valves are simultaneously adjusted.

11. In a carbureter, the combination of a chambered body provided with an annular valve seat, the chamber above the seat constituting a mixing chamber and that below an air inlet chamber, a mixing chamber valve coating with said mixing chamber valve seat providing when open an unobstructed annular port, a carbureting chamber delivering to said mixing chamber centrally above its said port, a fuel nozzle disposed to deliver centrally to said carbureting chamber, an annular carbureting chamber air inlet valve surrounding said nozzle providing an annular air inlet port for said carbureting chamber, a needle fuel valve extending into the delivery orifice of said fuel nozzle to provide an annular fuel port delivering centrally of said carbureting chamber air inlet port, and means for simultaneously adjusting said valves.

12. In a carbureter, the combination of a chambered body provided with an annular valve seat, the chamber above the seat constituting a mixing chamber and that below an air inlet chamber, a mixing chamber valve coating with said mixing chamber valve seat providing when open an unobstructed annular port, a carbureting chamber delivering to said mixing chamber centrally above its said port, a fuel nozzle disposed to deliver centrally to said carbureting chamber, an annular carbureting chamber air inlet valve surrounding said nozzle providing an annular air inlet port for said carbureting chamber, a needle fuel valve, and means for simultaneously adjusting said valves.

In witness whereof, we have hereunto set our hands and seals in the presence of two witnesses.
